CHEMICAL REFINING OF LIGHT OIL
DISTILLATESFrank A. Apgar, Chicago, Ill., assignor to Sinclair
Refining Company, New York, N. Y., a corpora-
tion of Maine

Application April 15, 1950, Serial No. 156,209

4 Claims. (Cl. 196—30)

1

My invention relates to improvements in the sweetening of sour light oil distillates by treatment with copper chloride. In particular, my invention relates to an improved method for sweetening and desulfurizing mercaptan-sour light oil distillates by treatment with copper chloride to convert the mercaptans present to disulfides and to a simplified and more economical elimination of the bulk of the disulfides from the treated distillate.

Light oil distillates produced as petroleum solvents and light naphthas usually contain mercaptans. These mercaptans give the distillates an objectional odor and must either be removed or converted to a non-objectionable form, namely disulfides, by a sweetening process. A particularly advantageous method for sweetening mercaptan-sour light oil distillates is to treat the sour distillate with copper chloride so as to convert the mercaptans to corresponding disulfides which have no objectional odor in contrast to mercaptans from which they were formed and which show no reaction in the copper strip corrosion test ASTM D130-49T. Stocks containing disulfides of limited concentrations are acceptable to many consumers. The trend in the solvent trade, however, is to demand finished stocks which meet the distillation flask corrosion test in which the copper strip is placed in a flask containing the treated stock which is then distilled to end point. Under the conditions of this test, the disulfides present split up to give corrosive substances which blacken the copper strip. Thus it has become necessary to not only convert mercaptans to disulfides in solvent finishing, but to remove the disulfides from the treated stock. In conventional operation, the removal of disulfides is exceedingly difficult and time consuming because the dissociation temperature of the disulfides formed in the sweetening operation is normally below the end point of the finished stock. On redistillation of the treated stock to the end point of the untreated stock, the disulfides dissociate in part to mercaptans which are distilled with the overhead stream so that the sweetening operation is nullified to a large extent. If the mercaptan content of the overhead stream is sufficient to produce a poor copper strip or distillation flask corrosion test after reconversion to disulfides, the stock must be again treated and redistilled as before until the final product meets specifications. The conventional procedure requires a large amount of intermediate tankage, is time consuming and reduces net throughput of existing equipment.

According to my invention, the residence time of disulfides formed in the sweetening operation is reduced in the distillation operation to such an

2

extent that relatively little dissociation of the disulfides to mercaptans can take place. I have found that including a quantity of high boiling hydrocarbons in the treated distillate so as to provide a bottoms fraction in the distillation step which boils above the specification end point of the stock under production and continuous removal of the bottoms fraction during distillation effects a substantial removal of the disulfides before dissociation occurs. Thus my invention provides for production of a specification stock in one pass and eliminates the necessity of re-treating the stock, as is necessary in conventional operation to meet the distillation flask corrosion test. The residence time of the disulfides and consequently the mercaptan content of the overhead product are reduced by increasing the amount of higher boiling hydrocarbons in the untreated stock boiling higher than the end point of the desired product. Advantageously, the quantity of higher boiling hydrocarbons approximates about 8 or 10 to about 20 per cent on the feed, and the material may comprise either a "tail" on the stock or extraneous bottoms.

25 My invention will be further illustrated by reference to the accompanying drawing which represents a diagrammatic flow plan.

In the drawing a mercaptan-sour light oil distillate is charged to the sweetening operation by pump 10 and line 11 through heat exchanger 12. Heat exchanger 12 may operate as either a pre-heater or a cooler in order to better control operation in the primary copper chloride contact tower 13. The sour feed stock may be introduced 30 either to the bottom of the copper chloride tower 13 as by line 15 and dispersing means 16 or to the top of the tower if desired. Air is introduced to the bottom of the copper chloride tower 13 by means of connection 17. The treated stock is 35 removed from the top of tower 13 through valved line 19. The treated stock is passed through air release tower 20 from which air is released overhead through line 21, and the de-aerated stock is removed at the bottom through line 22. The 40 stock is passed through heater 23, which may be heated by 150-pound steam circulation, into solvent rerun tower 24. The disulfides produced in the copper chloride treating tower 13 are removed with a bottoms fraction withdrawn through line 45 25 into drum 26, which may be employed as a reboiler drum employing steam as the heating medium. Lighter material is returned to the solvent rerun tower 24 through vapor return line 28, while the bottoms and disulfides are withdrawn from the system through line 27. The 50 treated and redistilled stock is withdrawn overhead from the solvent rerun tower 24 through line 29 and cooler 30 to accumulator 31, which

is vented to the atmosphere. Advantageously, the accumulator temperature is maintained high enough so that the vapor pressure of the stock is slightly greater than atmospheric. Consequently, a small amount of vapor escapes to the atmosphere and prevents air from backing up through the accumulator 31 to the condensers. Contacting air with the overhead stream is undesirable because it may result in oxidation of any hydrogen sulfide present from disulfides dissociating to elementary sulfur, which would give a bad copper strip test on the product. A portion of the stock from accumulator 31 may be returned to the solvent rerun tower 24 as reflux through line 32. The bulk of the stock, however, is passed through line 33 and cooler 34 into caustic wash tower 35. In order to obtain better mixing, the stock is advantageously injected into tower 35 through an eductor and spray nozzle system 36. Caustic recirculation is effected through line 37 and the eductor. The washed and separated stock is taken overhead through line 38 to rock salt tower 39, which is packed with rock salt and is designed to remove entrained moisture and caustic soda solution. The dried stock is removed to a secondary copper chloride treating tower 43 through line 42. Air for regenerating the copper chloride may be admitted as by line 41 at the foot of the rock salt tower 39 or at the foot of the secondary tower 43, or the operation may be conducted in a split tower in which the bottom half of the tower is packed with rock salt and the top half with the copper chloride treating mixture. Dispersal aids 40 and 44 may be provided in contact towers 39 and 43. The finished, sweetened stock is removed to tankage through line 45.

The feed stock of the sweetening operation contains mercaptans in the boiling range of the stock but should be clear, i. e., moisture free and free of hydrogen sulfide and elementary sulfur. Advantageously, therefore, the stock is subjected to a preliminary sodium hydroxide solution wash, followed by passage of the stock through a salt tower. The stock to be treated should be paraffinic or aromatic in nature and free of olefins. According to my invention, it must contain a sufficient quantity of hydrocarbon material boiling above the end point of the desired finished product to permit removal of the bulk of the disulfides with the bottoms fraction in the solvent rerun tower so as to reduce the residence time of the disulfides in the distillation tower to a minimum and thereby effectively limit re-formation of mercaptans by dissociation.

In the copper chloride treating tower, the mercaptans are converted to corresponding disulfides by oxidation with copper chloride. By adding oxygen to the chemicals in the treating tower, the resulting cuprous chloride may be reverted to the cupric form. To improve the operation, it is advantageous to supply a powdered or granular water-absorbent, chemically inert material of sufficient structural strength to permit handling with the copper chloride in the treating tower. For example, dry Olmsted earth of about 16 to 30 mesh is suitable. It also is highly desirable to slurry the copper chloride with water before mixing with the adsorbent carrier. If the copper chloride and adsorbent carrier are mixed dry, the materials in the treating bed tend to be hydraulically classified, with the copper chloride particles generally rising to the top of the bed. Copper carryover or entrainment occurs with subsequent corrosion problems in the equip-

ment. I have found that an especially satisfactory charge to the treating tower consists of water, copper chloride and adsorbent carrier in the approximate weight ratio of 1:1:4.

Since water is formed in the regeneration reaction, it is necessary to remove water from the system to maintain a satisfactory water ratio in the copper chloride bed. If the water content of the copper chloride charge is appreciably below this amount, copper carryover begins; if the water content rises appreciably above this amount, the copper chloride charge tends to "mud up" or channeling results with formation of copper mercaptides as a result of incomplete conversion of the mercaptans to the disulfides. The formation of copper mercaptides results in copper carryover with subsequent severe corrosion difficulties.

Water removal is effected by its solubility in the stock being treated. Control of the water ratio in the copper chloride bed is maintained by controlling the temperature of the stock in the treating tower within the range approximating 85 to 115° F. by means of appropriate preheating or precooling. The temperature of the stock undergoing treatment is important because the solubility of the water in the hydrocarbon stock and thus the rate of removal from the system is a function of temperature. Thus, if the bed becomes too wet, the temperature should be raised, whereas if the bed is too dry, the temperature of the feed stock should be lowered. A convenient control test is by observation of copper carryover through reaction with diphenylthiocarbazone reagent. For example, when a positive copper test is observed, the preheat may be raised 5° F. If the copper test is negative in a short time, e. g., 1 to 2 hours, it is apparent that the bed was too wet and the increase in preheat should be at least partially maintained. If the copper test is still positive, the bed is too dry and the stock should be precooled. Generally, I have found that the feed should be preheated 3° to 5° F. for a mercaptan-sulfur content of 7 mg. per 100 cc. for the feed stock.

As noted above, oxygen is required for in situ regeneration of the copper chloride treating material, and air is advantageously used for this purpose. Approximately $\frac{1}{2}$ mole of oxygen is required for 2 moles of mercaptan reacted. The oxygen required per barrel treated per hour approximates 0.015 cubic foot per 1 mg. of mercaptan sulfur per 100 cc. of sour stock. Thus, for a 7-mg. mercaptan-sulfur stock, the air required is equal to $0.015 \times 5 \times 7$ or 0.525 cubic foot of air per barrel per hour. Actually, contact is only about 20 per cent efficient, so that I recommend about 2.5 cubic feet of air per barrel per hour for a 7-mg. mercaptan-sulfur stock. Also, it is advantageous to employ an excess of air in order to immediately react with hydrogen chloride liberated in the treating reaction, so as to assure regeneration of the copper chloride particles and to prevent corrosion difficulties in the subsequent equipment.

In operation, it is desirable to release excess air from the treated stock before redistillation to avoid the possibility of obtaining explosive hydrocarbon and air mixtures in the distillation stage. The stock from the air release tower is preheated and sufficient bottoms are continuously removed in the distillation stage to reduce the residence time of the disulfides in the distillation zone and thus reduce the amount of disulfide breakup. Since a small amount of dis-

sociation may occur even with continuous removal of a large proportion of the stock as bottoms, the redistilled stock is washed with dilute aqueous caustic soda, e. g., about 25° Bé., to remove any hydrogen sulfide that may have been formed by the dissociation. Entrained moisture or caustic solution is then removed in a salt tower and any mercaptans in the overhead product from the distillation stage are converted to disulfides in a secondary copper chloride treating tower. The conditions in the secondary treating tower are substantially the same as those obtaining in the primary treating tower.

I have found that the quantity of bottoms continuously withdrawn in the distillation stage should be 10 per cent on the feed or more. For example, in treating a 10-mg. mercaptan-sulfur per 100 cc. stock for production of a 310° to 390° F. solvent, the reboiler temperature on the solvent rerun tower was operated at 415° to 425° F. With 1 per cent bottoms withdrawal based on the feed, the mercaptan-sulfur in the overhead product was 2.5 mg. per 100 cc. At an 8-per cent bottoms withdrawal, the mercaptan-sulfur in the overhead product was 0.9 mg. per 100 cc. With 20 per cent bottoms withdrawal, the mercaptan-sulfur in the overhead product was 0.5 mg. per 100 cc. In general, I have found that for a 6 to 7 mg. mercaptan sulfur stock, 10 per cent bottoms withdrawal results in an overhead product containing not more than 0.3 to 0.6 mg. of mercaptan-sulfur per 100 cc. A bottoms withdrawal of more than about 20 per cent based on the feed does not produce a sufficient reduction in mercaptan-sulfur to justify the uneconomic handling of the stock.

The following tests on experimental blends made up from stocks handled in a run producing a 300° to 400° F. solvent, taking 20 per cent bottoms on the feed at a 425° F. reboiler temperature, illustrate the necessity of reducing the disulfide content of the finished solvent to less than about 1 mg. per 100 cc. to pass the distillation flash corrosion test.

Hence my invention provides a system for treating raw mercaptan-sour solvent stock in a one-pass operation to a finished stock that will pass both copper strip and distillation flask corrosion tests. The use of intermediate run-down tanks and the necessity of repeated re-treating of the finished stock are eliminated. The amount of disulfides in the finished stock may be controlled by varying the bottoms withdrawal in the distillation stage, and a substantial decrease in the total sulfur content of the stock may be effected.

I claim:

1. In a process for sweetening mercaptan-sour light mineral oil distillates by treatment with copper chloride to convert mercaptans to disulfides followed by distillation of the treated stock wherein disulfides have dissociation temperatures

below the end point of the finished stock, the improvement which comprises adding about 8 to about 20% by weight on the treated distillate charge to the distillation step of high boiling hydrocarbons in the distillate to provide a bottoms fraction in the distillation step boiling above the specification end point of the distillate and continuously removing said bottoms fraction containing disulfides during the distillation step in an amount of at least about 8% by weight on the treated distillate charge to the distillation step.

2. The improvement of claim 1 in which the bottoms fraction represents about 10 to about 20 per cent on the treated distillate charged to the distillation step.

3. The method of sweetening and desulfurizing light mineral oil distillates which comprises contacting a distillate having added therein about 8 to about 20% by weight on the treated distillate charge to the distillation step of hydrocarbons boiling higher than the specification end point of the distillate in a treating step with copper chloride, water and a solid water-absorbent material in the approximate weight ratio 1:1:4 in the presence of air to convert the mercaptans in the distillates to disulfides having dissociation temperatures below the end point of the finished stock, removing excess air from the treated distillate and redistilling the treated distillate to recover the distillate of specification end point as an overhead product while continuously removing the higher boiling hydrocarbons containing disulfides as a bottoms fraction in an amount of at least about 8% by weight on the treated distillate charge to the distillation step.

4. The method of sweetening and desulfurizing light mineral oil distillates which comprises contacting a distillate having added therein about 8 to about 20% by weight on the treated distillate charge to the distillation step of hydrocarbons boiling higher than the specification end point of the distillate in a treating step with copper chloride, water and a solid water-absorbent material in the approximate weight ratio 1:1:4 in the presence of air to convert the mercaptans in the distillates to disulfides having dissociation temperatures below the end point of the finished stock, removing excess air from the treated distillate, redistilling the treated distillate to recover the distillate of specification end point as an overhead product while continuously removing the higher boiling hydrocarbons containing disulfides as a bottoms fraction in an amount of at least about 8% by weight on the treated distillate charge to the distillation step, washing the redistilled distillate with aqueous caustic soda, removing moisture from the washed distillate by contacting with rock salt and re-contacting the distillate in a second treating step with copper chloride, water and a solid water-absorbent material in the approximate weight ratio 1:1:4 in the presence of air.
